CARBURETOR

David E. Hartshorn, Dobbs Ferry, N. Y.

Application February 16, 1932, Serial No. 593,288

15 Claims. (Cl. 261—44)

My invention relates to an improvement in carburetors for internal combustion engines, or other purposes.

An object of my improvement is to simplify the construction and adjustment of such carburetor devices and to increase their efficiency and reliability in operation. Further objects and advantages will be apparent on reference to the drawings in view of the following specification, 10 relating to this invention.

In the drawings:

Fig. 1 shows diagrammatically in partial cross section a possible embodiment of the invention.

Fig. 2 shows a modification of the mixing venturi.

Fig. 3 is a section on the line 3—3 of Fig. 1 or 2.

Fig. 4 is a section on the line 4—4 of Fig. 1 or 2.

Fig. 5 shows details in a partial vertical section through a carburetor according to this invention.

Fig. 6 is a horizontal section on the line 6—6 of Fig. 5.

Fig. 7 is a broken vertical section on the line 7—7 of Fig. 5.

Fig. 8 is a section on the line 8—8 of the Fig. 6.

Fig. 9 is a section on the line 9—9 of Fig. 5.

Fig. 10 is a section on the line 10—10 of Fig. 6, 30 and Figs. 11, 12 and 13 are alternative sections on line 11—11 of Fig. 5.

The carburetor in the embodiment of Fig. 1 has the usual float valve chamber indicated generally as 18 with the float 11 for controlling admission of fuel from the line 12. The usual or known details may be employed for admitting fuel to the means feeding the Venturi chamber indicated generally as 14.

The main body 15 of the venturi maintains its ideal tapering and proportions for the most advantageous vaporization of the fuel by employing a plunger or movable member 16 telescoping within the main body 15 of the Venturi chamber. The size of parts may be proportioned, 45 however, so that the movable member may telescope over the other member. The movable member 16 may be linked to throttling devices through a straight line linkage or by more simple means indicated as the hingedly mounted levers 17 and 18. The main body 15 may be provided with guiding extensions on which the movable member 16 may readily slide. Adjusting means mounted on either member may determine the range of movement of the movable member to avoid unintentionally throttling the

engine to a stall or to avoid over speeding the engine. Guideways 19 in the venturi are optional. The usual heating jacket may be employed on the outer Venturi member.

A fuel conduit member 20 traverses the vaporizing chamber in a line parallel to the motion of the movable member and is arranged in the venturi in an optimum relationship to the throat of the venturi. This is seen in Fig. 3 in cross section. A fuel conduit 21 is disposed longitudinally of the member 20 to receive fuel from the float valve chamber when needle valve 22 is lifted from its seat, by one of the methods to be described later. The member 20 extends within the movable member 16 and has a continuous slot 23 or a similarly arranged series of perforations in the upper side of the member 20 in communication with the conduit 21. The slot may be of uniform width in the portion of the member 20 that may be exposed in the Venturi chamber. The slot may alternatively be of increasing or decreasing width as seen in Figs. 11 and 12 and possibly longitudinally as well depending on the nature of the fuel or the characteristics of the motor for which the carburetor is to be designed. Perforations, that may be employed instead of the slot 23, may similarly be tapered in cross section or in spacing or both as desired. The member 16 may be fitted to seal the slot 23 or perforations over which it has passed. Additional fuel conducting means may be provided in the member 20 to feed the fuel slot or perforations adjacent the remote end of the member 20. A larger perforation or bore could connect such an additional fuel conduit to the main or higher fuel conduit.

Control of the fuel flow through conduit 21 may be by means of a rod 25 fitted within the conduit 21 and adapted to move with the movements of the movable throttling member 16. 40 This rod may carry a small upstanding fin 125 to seal and sweep the slot 23 to prevent clogging. Increase in size of the fuel perforations or of the slot 23 is made available by increase in known bleeding. Air is bubbled into the fuel stream in 45 controllable amounts to vary the richness or leanness of the fuel mixture passed into the Venturi stream. Adjustability of the rod 25 relative to the movable member 16 may be accomplished in any way as by a nut 26 held by a stop 50 27 and threaded to cooperate with threads on the rod 25. The rod member is movable to vary the open length of conduit 21 in a manner to compensate for changing conditions of operation such as from winter to summer. The rod 25 may 55

have a squared end or a wedge shaped end in which latter case the rod is to be arranged with its sloped face toward the slot 23 to decrease or taper the flow of fuel inwardly from its end.

5 The venturi may be connected at its bottom to an air intake 30 and be provided with a drip pan 31. The air intake may be of any of the known types including air filtering and/or optional hot spot heating.

10 The needle valve 22 may be lifted from its seat, sealing the end of the passageway 21, by a rotatable member 35. The lifting of needle valve 22 by member 35 may be through an adjustable connection to the throttling lever 18 arranged to vary 15 the rate of opening, or through a choke connection such as 36 seen in Figs. 6 and 10 for flooding the engine in cold starting. Alternatively, an independent choke inlet may be employed for flooding the venturi and the place of combustion such 20 as the cylinders of an engine. An optional means for lifting the needle valve from its seat is seen in a vacuum connection 38 to the intake manifold 39. The suction from the intake manifold 39 through the connection 38 operates on a 25 piston 40 in a cylinder 41. A spring 42 may hold the needle valve on its seat and be adjusted to the proper tension by a spider 43, movable by a threaded screw 44.

The embodiment in Fig. 2 shows tapering of 30 the Venturi chamber by flare in its walls both as in Fig. 1 and at right angles to the tapering of the venturi illustrated in Fig. 1 and Fig. 3 and additional thereto. A member 115, shown in part, constitutes a closure for the float valve chamber and is the fixed member of the venturi. A member 116, shown in part, constitutes the 35 movable plunger or throttle of the carburetor as in Fig. 2. The carburetor of Fig. 2 connects to an intake manifold 139. The Venturi wall of plunger member 116 and the opposing wall of member 115 may be rounded out hollow to improve the venturi characteristics somewhat as seen in Fig. 6. The other or side Venturi walls in any embodiment of this invention would be plane 40 to provide a reasonable fit between the fixed member and the plunger member for sealing the Venturi chamber against undesirable leakage.

The bleeding or bubbling of air into the fuel 45 stream into the venturi air stream is accomplished by connections somewhat as seen in Figs. 5 and 6. A fixed Venturi member 215 and a movable or plunger Venturi member 216 cooperate with a fuel conduit member 220 to produce the 50 desired explosive mixture for power in the engine. The fuel conduit in member 220 consists of a long bore 121 variably stoppered by the rod 225. The additional fuel conducting means 221 are in full 55 communication with the bore 121 and together they give a large wall area for bleeding purposes. Perforations 222 slope upwardly from one inner face of this fuel conduit to open air and one or more of these perforations or ports may be selectively open to air. The projecting member 60 65 223 bored for these perforations 222 may be shaped to retain a fine gauze cap to prevent entry of grit or may have any suitable cover of variable opening or openings to be used in testing the carburetor for the effects of varying bleeding into the carburetor.

70 It is known that for acceleration or for heavy load relatively more power or heat is required calling for a richer fuel mixture than for mere economical operation. A series of supplementary 75 bleeding inlets 227 is arranged entering the other

face of the fuel conduit to be variably opened depending possibly on the load carried by the engine. The variable opening of bleeding inlets 227 is accomplished since use is made of the fact that during acceleration or heavy load there 5 is less suction in the intake manifold and less suction in any conduit entering the intake manifold. The fall in value of the suction is employed to decrease bleeding of air into the fuel conduit. Additional bleeding conduits 227 are 10 thus controlled to be fully operative only for lighter loads and variably or increasingly blocked by a piston 228 when an ever richer fuel is needed for ever heavier loads.

15 Piston 228 is shown as a hollow capped cylinder, 15 spring pressed by spring 229 into a position at the extremity of control cylinder 230. The spring 229 is of suitable stiffness and its response can be varied by a screw frame or system 232. A cap 233 threads into the cylinder and holds screw 20 frame 232 in its adjusted position. A suction conduit 234 of suitable size connects into the intake manifold to cause piston 228 to respond promptly to changes in pressure conditions at that controlling point. The various most suitable fuel mixtures are thus obtainable over a wide range of operation by proper choice in the area of the fixed bleed openings 222 and the area 25 range of bleed openings 227. The projecting member 237 carrying bleed holes 227 may also 30 have gauze capping means.

The embodiment of means for variably controlling the gas flow is seen in a gas throttle member 37 having a cam surface 371 that running 35 on a flanged rotor or wheel 372 with a fixed axis 373 presses upwardly on a similar flanged rotor or wheel 314 on axis 375 to rock the lifting member 351 for needle valve 322, through axis 376. The respective locations of the rotor member 374 and its supporting shaft 375 about which it rotates can be interchanged for an arrangement such as that of Fig. 1.

The cam accomplishes the variable movement of the needle valve by the choice of cutting or outline in its surface 371 which may have any form 45 either linear as shown or curved outwardly for more rapid opening at first or curved inwardly for a less rapid rate of opening at first with more rapid opening later. This latter or hollow cutting gives relatively greater flow of gas for acceleration or for greater load. The cam like gas throttle member 37 is adjustably connected to the throttling member such as 17 or 18 by adjusting means such as a turnbuckle 377.

The usual hot jacketing of the venturi to improve vaporization is accomplished by water jacket members 46 and 47. The hot water or heating medium enters the jacket member 46, through connecting pipe 48 and passes from the member 46 to member 47 through pipe 49. A 50 pipe 51 carries the cooled medium to the pump of the circulating cooling system for the engine.

The throttle rod 225 may have a slot 252 for additional guiding means 253 to save wear on the fin 125.

Fig. 11 shows the alternative type of fuel slot 23a having increasing width outwardly in conduit member 220a while Fig. 12 shows another alternative type of slot 23b in fuel conduit member 220b to accommodate different conditions or fuels 70 of different grades.

Fig. 13 shows an alternative arrangement of fuel outlet into the Venturi throat with a slot or slots 23c arranged at an angle to the air blast.

An adapter unit may be employed between the 75

carburetor and intake manifold fitting. This adapter can be of a size at one end to match a particular intake manifold and at the other end match a standard carburetor. Thinning and 5 mixing of the fuel stream can be accomplished in this adapter by circumferentially disposed ports variably blocked by reeds secured at one end and adapted to yield at the other end to suction to admit a thin stream of air for a condition of increased suction. The air jets admitted give the 10 intake mixture a sharp whirling effect. A rigid collar may be arranged to variably cover or entirely cover these ports to limit their range of operation or render them entirely inoperative. 15 Such a collar may be arranged to be operated from a distant point.

Changes in the present disclosure may be made by one skilled in the art without departing from the spirit or scope of the invention.

20 I claim:—

1. A fuel supply member with a central bore and slot means communicating to a vaporizing chamber, a throttle means for varying the area of slot in communication with the chamber and a 25 fin on the throttle means to fit in the slot and seal it or sweep the slot clean when moved relatively thereto.

2. A carbureting means for internal combustion engines including means, having a Venturi 30 chamber for mixing and vaporizing of fuel with a plunger member for varying the cross section of the vaporizing chamber, a stream lined fuel supply conduit traversing the mixing chamber adjacent the Venturi throat, means disposed along 35 the conduit for admitting fuel from the conduit into the throat of the venturi and a fuel regulating rod rigid with the plunger for effectively closing or opening the fuel admitting means in predetermined relationship with the plunger 40 movements.

3. A fuel supply conduit for the carbureting means of claim 2 characterized in that the rod is adjustable relative to the plunger member.

4. A fuel supply conduit for the carbureting 45 means of claim 2 characterized in that the fuel conduit has a continuous slot in the portion to be exposed to the mixing chamber and the fuel regulating rod has a fin projecting into the slot to sweep it clean in movements longitudinally of the 50 slot in the supply conduit.

5. In a carburetor a plunger for controlling the size of a Venturi passageway to throttle an internal combustion engine with a means adapted to variably dilute the fuel by mixing in air before 55 entering the fuel into the Venturi means through a slotted fuel conduit traversing the Venturi chamber, the slotting being of a configuration to pass the desired limited flow of the fuel mixture and disposed at the upper side of the fuel conduit.

60 6. A fuel supply means with a longitudinal bore having slot means communicating to a chamber, a throttle means to vary the slot area communicating with said chamber and means on the throttle means arranged to sweep said slot.

65 7. A fuel supply means having a Venturi type mixing chamber, a plunger member forming part of the Venturi chamber and arranged on movement to vary the cross sectional areas of the chamber to vary the capacity of the fuel supply means 70 while maintaining the taper of the venturi, a fuel supply member with a fuel conduit arranged traversing the Venturi chamber and communicating therewith and means carried by the plunger member for variably stopping the fuel conduit 75 both internally and externally.

8. A fuel supply means having a Venturi type mixing chamber, a plunger member forming part of the Venturi chamber and arranged to vary the cross sectional areas of the chamber to vary the capacity of the fuel supply means without varying the taper of the venturi, a fuel supply member traversing the venturi with a fuel conduit communicating with the Venturi chamber and means for variably throttling the fuel conduit in linear relationship with throttling of the venturi, 10 and both externally and internally. 5

9. A carburetor having a Venturi chamber provided with a plunger with its inner surfaces shaped as part of the venturi, a fuel conduit and spray means telescoping within the plunger, and 15 means cooperating with the plunger to vary the length of the fuel column in the conduit in accordance with motions of the plunger.

10. In a carburetor, a movable plunger for varying the size of the air passageway the 20 plunger being shaped to form a Venturi throat when associated with the fixed portion of the carburetor, a means controlled by changes in pressure of the fuel mixture due to movements of the plunger to vary admission of air to a stream of liquid fuel, and means traversing the Venturi throat, approximately centrally thereof for delivering the fuel mixture into the Venturi chamber. 25

11. A carburetor having a movable plunger 30 member as an air throttle for a Venturi mixing chamber, a fuel valve member mounted on the plunger to move therewith and guide means to check tendencies of the last member to rotate relative to the plunger member. 35

12. A carburetor having a Venturi chamber provided with a plunger with its inner surfaces shaped as part of the Venturi passageway, a fuel conduit member telescoping within the plunger and adapted to deliver fuel into said Venturi 40 chamber and means cooperating with the plunger to vary the length of the fuel column in the fuel conduit for any movement of the plunger.

13. In combination with an intake manifold, a carburetor having a conduit for liquid fuel, open 45 port means of adjusted area for admission of air into the fuel stream in the fuel conduit and supplemental air admission port means communicating with the fuel conduit, said supplemental port means being closed or variable in area under 50 control of the changing pressures in the intake manifold to have increased area for low pressure conditions in the manifold and to have reduced area for increased pressure in the manifold to enrich the fuel at higher loads. 55

14. In combination in a carburetor associated with an intake manifold, a fuel conduit for liquid fuel, a group of air admission ports entering the conduit to be selectively closed to adjust operating conditions over the whole operating range of the 60 carburetor and other air admission ports normally closed with means to selectively open the ports under control of varying conditions in the intake manifold.

15. A carburetor having a fuel conduit, a plurality of air admission ports entering the fuel conduit from one side and variable in number for permanent adjustment over the operating range for predetermined conditions, a plurality of air admission ports entering the conduit from 70 the other side and means to vary the working area of the last mentioned ports inversely with working conditions in the carburetor. 65
